United States Patent Office.

CHARLES HEWITT, OF TRENTON, NEW JERSEY.

Letters Patent No. 89,763, dated May 4, 1869.

IMPROVED METHOD OF CONSTRUCTING PILES FOR BEAMS.

The Schedule referred to in these Letters Patent and making part of the same.

To all whom it may concern:

Be it known that I, CHARLES HEWITT, of Trenton, Mercer county, and State of New Jersey, have invented a new and improved Method of Forming the Piles, preparatory to rolling iron girders, trough-bars, or other like bars; and I do hereby declare that the following is a full, clear, and exact description thereof, reference being had to the accompanying drawings, making part of this specification, in which—

Figs. 1, 2, 3, 4, 5, 6, 7, and 8, are cross-sections, representing my said improved method as applied to forming piles of various forms.

The same letters indicate like parts in the various figures.

In the manufacture of iron bars, of the character designated, it is desirable that the form of the pile should resemble, as near as may be, the form of the bar, after it has been completed, for the following reasons, viz:

First, so that the rolling may be accomplished by the use of a less number of grooves in the rollers than would otherwise be required, thereby finishing the bars in less time, at a temperature sufficiently high to insure a perfect weld and avoid flaws or defects in the completed bar, and, at the same time, to save the rolling-machinery from undue and dangerous strains; and

Second, so that the reduction of the iron in rolling may be more uniform in every part of the pile, and thereby avoid unequal and injurious strains which would otherwise weaken the resulting bar.

In the accompanying drawings—

Figure 1 represents a pile, such as prepared for rolling a girder, with a web and flanged head-pieces.

The head-pieces A A are formed each with a projecting rib, *a*, and the pieces B B, next to them, are formed with grooves, to receive the ribs *a a*, and the pieces B B, and the intermediate piece or pieces C, as there may be any number, depending upon the size of the girder, are formed with ribs and grooves, as represented, to form the web.

The grooves are made a little wider than the ribs, into which wedges, *b*, are driven, to hold together the several pieces constituting the pile.

Figure 2 represents a pile, arranged according to my improved method, and suitable for producing a bar without flanged head-pieces.

Instead of forming the two contiguous faces of two pieces, one with a rib and the other with a groove, both may be grooved, a square rod, *c*, inserted, and there secured by a wedge, or wedges, *b*.

Figure 3 represents a pile with one double-flanged head-piece, A, suitable for producing a bar of corresponding form. The lower piece D, of the web, has neither groove nor rib on the lower surface.

Figure 4 represents a pile, with two single-flanged head-pieces A A, suitable for producing a bar with two flanches on one side only.

Figure 5 represents a pile, with two head-pieces A A, one double-flanged and the other single-flanged.

In Figure 6, the pile has two head-pieces A A, both single-flanged, but on opposite sides.

Figure 7 represents a pile, with the double-flanged piece A in the middle of the pile, suitable for producing a bar, whose cross-section will be in the form of a cross; and

Figure 8 represents a pile, with one single-flanged head-piece.

The advantages due to my improved method of forming piles, are—

First, the facility with which the shape or size of the pile may be made to conform to that of any of the sections of iron, for which it is intended, without multiplying the forms of iron which it is necessary to prepare for the purpose.

Second, the stability of the pile, enabling it to stand all the necessary manipulation in the heating-furnace, and from the furnace to the rolls, without becoming distorted or dismembered.

Third, facility for the escape of the cinder in the process of rolling, thereby securing a better welding of the parts.

I have represented several forms of piles, to which my improved method is applicable, but I wish it to be understood that I do not limit my claim to such forms, as my invention is applicable to other forms.

I do not claim, as any part of my invention, the formation of piles, by the combination of plain flat bars, to form the web, with grooved bars to form the flanches, as I am aware that piles have been so made.

What I do claim as my invention, and desire to secure by Letters Patent, is—

My improved method of arranging piles for rolling bars of the general character herein pointed out, which method consists in composing the pile of a series of pieces, formed with ribs and grooves, and secured by wedges, substantially as described.

CHAS. HEWITT.
